CONCENTRIC MULTIPACTOR

Richard L. Snyder, Glasboro, N. J., assignor to
Farnsworth Television Incorporated, San Francisco, Calif., a corporation of California

Application July 18, 1936, Serial No. 91,343

3 Claims. (Cl. 250—175)

My invention relates to electron multipliers and more particularly to that type of electron multiplier wherein electrons are directed to successively impact a series of emitter elements to produce a current augmented by secondary emission at each impact.

When a series of emitting elements are placed with relation to each other and maintained at successively increasing potentials so that electrons may be drawn from one to another until the entire series has been impacted, the degree of multiplication depends, among other things, upon providing electron paths offering a minimum limitation of flow thereof along such paths.

15 Among the objects of my invention are: to provide an electron multiplier arranged to provide a high degree of multiplication; to provide a compact multiplier unit; to provide an arrangement and construction in an electron multiplier whereby electrons themselves in the aggregate determine their own paths; and to provide a structural arrangement of an electron multiplier calculated to facilitate simplicity in manufacture.

Other objects of my invention will be apparent or will be specifically pointed out in the description forming a part of this specification, but I do not limit myself to the embodiment of the invention herein described, as various forms may be adopted within the scope of the claims.

30 Referring to the drawing:

Figure 1 is a sectional view of an electron multiplier;

Figure 2 is a sectional view from line 2—2 of Figure 1; and

35 Figure 3 is a sectional view from line 3—3 of Figure 1.

In the preferred embodiment the electron multiplier comprises an evacuated, cylindrical envelope 1 closed at both ends by end walls 2 and 3. Sealed through the central input stem 4 in end wall 2 are the leads 5 of the filamentary cathode 6 and the lead 7 for a control grid 8. Mounted as by lead 9 sealed in stem 10 in end wall 3 with its surface normal to and with its center preferably coincident with the axis of the envelope is a disk 11. The surface 11a of disk 11, which is disposed toward the cathode 6, is sensitized for secondary emission and may be sensitized for this purpose by having deposited thereon a coating of thorium, caesium, or the like. Disk 11 is surrounded by a similarly sensitized flat ring 12 mounted in the same plane but spaced therefrom and providing a second secondarily emissive surface 12a, and being mounted upon a lead in 13 sealed through stem 10. A

pair of similarly shaped rings 14 and 15 are concentrically mounted with respect to each other and to surround grid 8, leads 16 and 17, respectively, being secured thereto and sealed through stem 18 for the purpose. The ring 14 is sensitized for secondary emission. An open mesh accelerating anode 28 is provided midway of the tube and energized to a higher potential than any of the other electrodes by battery 29. This prevents electrons from going to an electrode of 10 higher potential on the same side of the tube.

5 Filament 6 is energized from a source 19 and electrons from the filament are accelerated by anode 28 toward the sensitized surface of disk 11 under control of grid 8. In order to provide 15 necessary energization of emitter elements a resistor 20 is connected across the potential source 21, taps 22, 24, 25 and 26 leading respectively to the cathode 6, and the emitter elements 11, 14 and 12 to produce progressively increasing 20 potentials thereon, the end of the resistor being connected to the anode ring 15 through lead 17 and an output impedance 27, the latter being so connected that variations in current therefrom may be utilized.

25 Energized as described above, electrons leaving the filament 6 pass through grid 8 and are accelerated to the first emitter element 11a in the series and a larger number of secondary electrons are emitted therefrom. These secondary 30 electrons are drawn across the tube to the second emitter element 14a and cause the emission therefrom of a still larger number of electrons, these latter secondaries being drawn to the opposing emitter element 12a for the release therefrom of a still further multiple of the impacting electrons. The electrons released from element 12a are drawn to anode 15 for utilization in the output impedance 27.

35 It will be observed that the respective areas 40 of the emitter elements 11a, 14a and 12a are preferably progressively greater and that this progression corresponds to the progressively increasing number of electrons which impact these surfaces. This arrangement tends to maintain 45 electron densities in the space between successive elements within desirable limits, thus minimizing any tendency to create space charges. As indicated by the arrows in Figure 1, the successive paths of the emitted electrons tend outwardly of the tube axis and those in each path tend to cause those in the succeeding outer path to deflect outwardly, these tendencies being overcome by the potentials on the emitter elements. On the other hand, the preponderance of elec- 55

trons moving in the outer spaces, as for instance in the space between the emitter 12a and anode 15, tend to maintain those in the inner inter-element spaces directed toward the proper emitter elements.

5 It will be apparent that simplicity and compactness of this electron multiplier are coupled with the facts that the arrangement is inherently advantageous from the standpoint of minimum space charge limitations and efficiency in 10 causing electrons to follow proper paths without special focusing means.

Having described a preferred embodiment of 15 my invention, it will be evident that various modifications may be made by those skilled in the art without departure from its true spirit. Accordingly, I wish it to be understood that I consider myself entitled to all such modifications as properly lie within the purview of the claims.

15 I claim:

20 1. An electron multiplier comprising a closed

envelope, means for producing electrons therein, means therein capable of releasing electrons by secondary emission comprising a plurality of spaced groups of concentrically spaced elements, each group being in the same plane.

2. An electron multiplier comprising a cylindrical envelope, means providing spaced groups of concentrically related secondary emissive surfaces at the ends thereof, each group being in the same plane, and means for directing electrons against an inner surface to release secondary electrons therefrom.

3. An electron multiplier comprising an envelope, a series of concentrically mounted washer-like surfaces capable of emitting electrons by 15 secondary emission therefrom, means for directing electrons serially against said surfaces to cause secondary emission therefrom, and means for collecting electrons emitted from the other surface.

RICHARD L. SNYDER.
